UNITED STATES PATENT OFFICE.

ABRAHAM G. SHIDEED, OF LAWRENCE, MASSACHUSETTS.

STOP-MOTION.

No. 885,875.

Specification of Letters Patent.

Patented April 28, 1908.

Application filed October 23, 1907. Serial No. 398,798.

To all whom it may concern:

Be it known that I, ABRAHAM G. SHIDEED, a citizen of the Empire of Turkey, residing at Lawrence, in the county of Essex and State of Massachusetts, have invented certain new and useful Improvements in Stop-Motions, of which the following is a specification.

My invention relates to drawing boxes for woolen and worsted roving particularly for worsted.

It is a stop motion for such drawing boxes and its purpose is to stop the machine whenever a break occurs in the sliver ends or in the roving.

In the drawings, Figure 1 shows in perspective a portion of the machine with certain parts broken away to show the construction. Fig. 2 is a front view and Fig. 3 is a side view of the stopmotion trigger action. Fig. 4 is a detail of the spindle and bobbin in action. Fig. 5 is a detail showing the action of a broken end upon the cup. Fig. 6 is a detail of the cup and finger. Fig. 7 is an elevation of the cup and Fig. 8 is a section of the cup and the end of the spindle bracket on line X Y of Fig. 9. Fig. 9 is a perspective view of the spindle bracket.

The purpose of such machines is to twist the ends A of the sliver as they are delivered from the drawing rolls G and H to form the roving K and to wind the roving upon the bobbins B. The spindles C, C are actuated by pulleys E, E. Each spindle C carries a flyer F provided with eyes 10 and 11 and each is in the form of a tube at its upper end through the sides of which is an opening 12.

The bobbins B, B are loosely mounted upon the spindles C, C, and rest upon friction washers L, which rest upon plates M fastened to lifter plate N. They could revolve freely upon spindles C, C were it not for the friction of washers L.

Each sliver end A is delivered by the rolls G and H and passes through the top of the spindle C out through the opening 12 and through one of the eyes 10. From thence it is wound around the arm of the flyer F and passes through the eye 11 onto the bobbin B. The bobbin B is rotated by the drag of the roving K coming from the arm of flyer F, but at a slower speed than the flyer on account of the drag of washer L, with the result that a twist is imparted to the roving and it is also wound upon bobbin B. It is distributed evenly upon bobbin B by the rise and fall of

lifter plate N. This is the "washer drag" system.

The bottom of each spindle C rests in a suitable opening in a pulley E, each of which is actuated through belts and pulleys of well known construction by fast pulley O on shaft 40.

In the well known type of machine to which this device is applicable, the spindle is supported at the top by a spindle bracket 30 into which sets the bearing cup 50 which can be passed over the top of the spindle C and pushed into the opening in the bracket and dropped into place therein, thus detachably holding the spindle in place.

The cup 50 consists of a tube 51 of such size as to form on its inside a bearing for the spindle C and on its outside to pass through a slot 31 on the upper outer end of spindle bracket 30. Cup 50 at its top 52 is flanged to set in the enlarged groove at the top of slot 31 forming a socket 32 which is of such size as to receive it closely. Socket 32 is of such size as to prevent cup 50 from getting out unless it is lifted. The top of the cup 50 projects somewhat above and the bottom somewhat below the bracket 30.

To put spindle C in place, its lower end is pushed through bobbin B, washer L, plate M, and lifter plate N, into its opening in pulley E. Cup 50 is placed on top of spindle C and is raised so as to pass its lower portion 51 through slot 31 until the upper flange 52 can be and is dropped into the socket 32 where it is held unless lifted in some way.

Each spindle bracket is provided with a rocker arm 60. Each rocker arm 60 is pivoted at 61 to block 62 which is fastened on the top of the lower part of the bracket 30 near where it is attached to the rail R. 95 Rocker arm 60 is bent at one end to conform substantially to the shape of the bracket 30. At its upper extremity rocker arm 60 is bent to form a cup finger 63 which projects sidewise over onto the top of the cup 50. The other end 64 of rocker arm 60 is straight and extends back into the machine.

The pivot shaft 70 which rests in bearings 71, 71 suitably attached to the frame of the machine behind the spindles, carries a plurality of contact arms 72, 72 provided with upwardly projecting forked ends in which rest the straight ends 64 of the rocker arms 60. There is one contact arm for each 110

rocker arm. A trigger arm 73 is also carried at a suitable point by pivot shaft 70. To counterbalance the weight of arms 72 and 73, I provide a counterweight arm 74 upon 5 which is the counterweight 75 detachably attached thereto by means of a set screw.

In this type of machine, the belt is thrown from the fast pulley O to the loose pulley P by a shipper connection operated by a 10 handle 80 carried by a shipper shaft 81. I fix a shipper arm 82 to the shipper shaft 81 and pivot to the shipper arm 82, a shipper rod 83 which is supported by and slides in bearings 84 and 85 fixed to any convenient 15 part of the machine. A collar 86 of greater length than the throw of the shipper rod 83 is adjustably attached thereto by means of a set screw. Around the shipper rod 83 resting at one end against the bearing 84 and 20 at the other end against collar 86 is a spiral spring 87.

When the belt is brought on the fast pulley O by handle 80 to start the machine, the spiral spring 87 is compressed and collar 25 86 is brought into such position that trigger arm 73 will be brought up by the counterweight 75 in front of collar 86 thus retaining it in that position. It will be seen that if trigger arm 73 is depressed out of the way of collar 86, spiral spring 87 will expand carrying with it the collar 86, shipper rod 83 and shipper arm 82 and will throw the belt from the fast pulley O onto the loose pulley P thus stopping the machine.

35 The operation is as follows:—If a break occurs in the sliver end A or in the roving at any point, the drag of the bobbin will wind up the surplus roving and will then cease. In such case, the sliver end A will continue 40 to be delivered by the delivery rolls G and H and will fall over and wind up, as shown in Fig. 5, around the top of the spindle C. After a few revolutions the winding end will force the cup upward, as see Fig. 5, in contact with cup finger 63 on rocker arm 60. This will depress the straight end 64 of 45 rocker arm 60 which will force down contact arm 72 and trigger arm 73 from in front of collar 86, thus releasing the spiral spring 87 and stopping the machine. When the ends 50 are pieced, the action of throwing the belt onto the fast pulley O will push back collar 86, compressing spring 87, until it reaches such a point that trigger arm 73 will rise in

front thereof by the action of counterweight 55 75, thus setting the device for the next break.

What I claim as my invention and desire to cover by Letters-Patent is:—

1. In a stop motion for drawing boxes, a 60 spindle, a bearing cup at the top thereof, a spindle bracket provided with a socket for the bearing cup, a rocker arm pivoted to the spindle bracket and bent at one end over the bearing cup and straight at the other end, a 65 pivot shaft, a contact arm carried thereby which engages the straight end of the rocker arm, a counterweight carried by the pivot shaft, and a trigger arm carried by the pivot shaft, combined with a shipper arm, a shipper 70 rod pivoted thereto and slidably supported in fixed bearings, a collar fixed to the shipper rod, and a spiral spring between said collar and one of the shipper rod bearings. 75

2. In a stop motion for drawing boxes, a plurality of spindles, bearing cups at the top thereof, spindle brackets each provided with a socket for a bearing cup, rocker arms straight at one end and each pivoted to a 80 spindle bracket and bent at the other end over a bearing cup, a pivot shaft, a plurality of contact arms carried thereby each of which engages the straight end of a rocker arm, a trigger arm carried by the pivot shaft, and 85 means whereby the belt will be thrown from the fast to the loose pulley when released by the trigger arm.

3. In a stop motion for drawing boxes, a plurality of spindles, bearing cups at the top 90 thereof, spindle brackets each provided with a socket for a bearing cup, rocker arms straight at one end and each pivoted to a spindle bracket and bent at the other end over a bearing cup, a pivot shaft, a plurality 95 of contact arms carried thereby each of which engages the straight end of a rocker arm, a trigger arm carried by the pivot shaft, a spring actuated shipper rod, and a collar carried thereby at such a point as to 100 engage the trigger arm.

In testimony whereof I affix my signature in presence of two witnesses.

ABRAHAM G. SHIDEED.
